ANIMATED IMITATION HEARTH FIRE

Filed June 30, 1930

Fig. 1.

UNITED STATES PATENT OFFICE

FRANK A. GRITT AND FENTON STEWART, OF INDIANAPOLIS, INDIANA, ASSIGNEES TO
GRITT, INCORPORATED, OF INDIANAPOLIS, INDIANA, A CORPORATION OF INDIANA

ANIMATED IMITATION HEARTH FIRE

Application filed June 30, 1930. Serial No. 464,952.

This invention relates to apparatus whereby to provide imitations of hearth fires and substances therein adapted to represent combustible material such as wood or coal, the invention having reference more particularly to apparatus adapted to equip a fireplace in imitation of a hearth fire with a simulation of animation for natural fire flame effect.

10 An object of the invention is to provide an improved fireplace of such construction as to afford a realistic imitation of a hearth fire and likely to create in the mind of the observer such pleasurable impressions as a 15 result from the observation of a real hearth fire.

Another object is to provide improved apparatus whereby to obtain novel effects in a fire-place of a building in simulation of a 20 log fire and which shall be adapted to be arranged in association with andirons or fire-dogs that might be found in place.

A further object is to provide an improved apparatus that shall be of such construction 25 and unitary group arrangement as to be adapted to be installed either in a conventional fire-place or in an imitation fire-place, and which shall be capable of imitating extremely long flames of fire appearing to 30 emanate from a fire log.

A still further object is to provide a unitary hearth fire apparatus which shall be of such construction as to be adapted to be manufactured at small cost, conveniently 35 shipped at low rates, readily installed in a simple manner and shall be adapted to be durable and economical in use.

With the above-mentioned and other objects in view, the invention consists in novel 40 apparatus constituting means whereby to simulate a hearth fire having prominent tongues of fire as appearing in the back portion of a fire-place; the invention consisting also further in the novel parts and combinations and arrangements of parts as herein- 45 after particularly described and further defined in the claims appended hereto.

Referring to the accompanying drawing, —Figure 1 is a front perspective view 50 of a fire-place and hearth fire substantially

in accordance with the invention; Fig. 2 is a vertical transverse section, approximately through the median portion of Fig. 1; Fig. 3 is a horizontal section of the fire-place and top plan of the apparatus as arranged there- 55 in to fully attain the objects of the invention; Fig. 4 is a front elevation of an improved reflector as preferably constructed to constitute an important element of the invention; and Fig. 5 is a rear perspective 60 view of an imitation log or logs constructed so as to be adapted to be a base to support various parts of the improved apparatus.

Similar reference characters in the different figures of the drawing indicate corresponding elements or features of construction herein referred to in detail.

As explanatory of the accomplishments of the invention a familiar fire-place is illustrated and comprises a hearth or base 1, 70 a back wall 2, side walls 3 and 4 and a roof 5, which may be a built-in feature of a dwelling or may be a unitary portable shell-like imitation of a fire-place adapted to be inserted into a dwelling wall for ornamental purposes in the fire-place; a fuel holder, preferably a pair of andirons 6 and 6' are suitably arranged and used to support imitation combustible material which, in furtherance of the invention comprise imitation fire wood logs 7 and 8 integrally moulded together of suitable material as a shell without a back portion, the rearward edge of the shell being adapted to constitute 75 a frame which preferably is recessed so as to have a bearing seat 9 and cavities 10 and 11 with a dividing rib 12 in which there is an opening 13 to represent space between the logs which appear to be arranged one 80 upon another, the fronts of the logs being roughened and colored in imitation of tree bark. The shells of the logs preferably have also suitable openings 14 and 15 in their walls which may be in imitation of knot-holes or of holes caused by fire. Preferably 85 a pile of imitation ashes 16 is arranged on the hearth to represent accumulations resulting from burned logs.

In accordance with preferred construction, the lower portion of the under log shell 100

being adapted to be supported upon the beams of the andirons, a bracket arm 17 is secured to said lower portion and extends rearward, the arm having branches 18 and 19 on its end adapted to be supported upon the andiron beams. The bracket arm supports a socket 20 for an electric lamp 21 so as to be opposite to the fire-place back wall. A suitable reflector 22 is arranged so as to be behind the imitation logs and forward of the lamp, facing the back wall 2. The openings in the logs are covered by colored translucent material preferably consisting of a translucent sheet 23 which is arranged and suitably secured on the seat 9 so as to be between the logs and the back of the reflector. The reflector preferably is composed of pliable or flexible metal, such as sheet aluminum and preferably is slightly corrugated with relatively angular reversely pitched breaks or lines 24 and 25 so as to distort the light reflected thereby in a novel manner to cause realistic flame simulations 26 on the back wall 2, the flame effect being primarily caused by rotors or light-interrupters 27. The reflector has a suitable number of openings 28 therein to permit the passage of light directly from the lamp through the openings in the imitation logs, the light passing also under the lower log to the hearth and ashes thereon; and preferably the lower edge of the reflector has a notch 29 therein the better to illuminate the ash pile. A shade or light-interceptor 30 is arranged between the lamp and the back wall 2 to prevent light rays from directly reaching the back wall, and its front surface may be adapted to turn the light rays forwardly.

40 The rotary light-interrupter is of that type which has a crown-shaped upper portion so as to permit light to pass upward at an angle from the lamp to the reflector 22 which reflects the rays upward at a reverse angle onto the back wall 2 so as to produce the fire flame effect sufficiently high to be seen over the top of the upper log 7. Practically a rotor may be and in some cases is sufficiently large to extend about the shade which may be in such case supported directly upon the lamp instead of the particular arrangement herein illustrated in the interest of clearness of view. Preferably a translucent sheet or plate 31 is arranged at the bottom of the log or the lower one and extends rearward so that light from the lamp shall pass through it to the hearth; and, if it be desired that a slight glow appear on the ashes and the hearth, the sheet 31 may be integral with the sheet 23 which is tinted to produce a flame color effect.

55 Structurally the reflector may be variously supported so that it can be carried unitarily by the log structure, and it may be

provided with braces 32 supported by the log structure.

The face of the back wall 2 is covered by blended colors or tints to give flame color effect. 70

In practical use the electric lamp generates sufficient heat to cause surrounding air to rise and pass through the rotor and act on the blades thereof to turn the rotor, the result being light is reflected onto the back 75 wall 2 on which light and shadows are produced by the action of the rotor which interrupts the continuity of the light from the lamp, the shadows appearing as moving laterally and upward as tongues of flame 80 26 on the colored wall. A simulation of flickering fire is seen through the openings in and between the logs and also below the lower log quite realistically. 85

What is claimed is:

1. An animated imitation hearth fire having a backless imitation log shell with openings therein, colored translucent material seated in the log shell covering the openings, a lamp arranged rearward of the lower portion of the log shell, a distorting reflector arranged between the log shell and the lamp and facing towards the lamp, the reflector having openings therein to admit light from the lamp to the translucent material, and a rotary light-interrupter mounted upon the lamp. 90

2. An animated imitation hearth fire having an opaque imitation log front member provided with an opening in the wall thereof and a colored translucent sheet covering the opening at the back of the wall, a lamp and a rotary light-interrupter thereon arranged opposite to the rear portion of the log front member, and a distorting reflector arranged between the lamp and the log front member and facing towards the lamp, the reflector being taller than the lamp and having an opening therein for passage of light to the translucent sheet. 100

3. An animated imitation hearth fire including an opaque imitation fuel unit structure having separate openings therethrough, a bracket fixedly supported by the lower portion of the structure, an electric lamp and a shade therefor mounted on the bracket, the shade being behind the lamp, a rotary light-interrupter mounted upon the upper portion of the lamp, a distorting reflector arranged between the lamp and the unit structure to reflect light rays upward at an inclination over the top of the lamp, and a sheet of translucent material arranged between said openings and the lamp. 110

4. The combination of a fire-place hearth and a back wall, andirons arranged on the hearth, an imitation log supported upon the andirons and provided with an arm projecting between the andirons towards said back wall, the arm having lateral branches ex- 125 130

tending onto the andirons for support, an electric lamp and a shade therefor mounted on said arm, the shade being between the lamp and said wall, a distorting reflector 5 arranged behind the imitation log and facing towards said wall on a higher level than the lamp, the reflector being curved partially about the lamp, and a rotary light-interrupter mounted upon the lamp and operating over the top of the lamp.

5. An imitation fire including a fire-place with a tint colored back part, an imitation fuel unit on the fire-place opposite to the back part, an electric lamp arranged in proximity to the back part of the fire-place, a distorting reflector arranged opposite to and facing the back part to turn back light rays from the lamp onto the back part, the reflector being horizontally nearly co-extensive 15 in width with the back part and curved partially about the lamp, and a light-interrupter mounted rotatably upon the lamp.

6. An imitation hearth fire including a fire-place with a fire color tinted back part, 25 an imitation apertured fuel unit on the fire-place opposite to the back part, an electric lamp arranged in proximity to the back part of the fire-place, a shade arranged between the lamp and the back part, a sheet of translucent material arranged behind the fuel 30 unit and being co-extensive therewith to extend across all the apertures therein, a distorting reflector arranged opposite to the back part between the lamp and the translucent material and curved partially about 35 the lamp, the reflector being co-extensive with the fuel unit and the translucent sheet and having openings therein, and a light-interrupter rotatably mounted upon the lamp.

40 In testimony whereof, we affix our signatures on the 24th day of June, 1930.

FRANK A. GRITT.
FENTON STEWART.
